UNITED STATES PATENT OFFICE

HERMAN B. LERMER, OF NEWARK, NEW JERSEY, ASSIGNOR TO HYGIENIC TUBE AND CONTAINER CO., OF NEWARK, NEW JERSEY, A CORPORATION OF NEW JERSEY

DESIGN FOR A MEDICINAL CONTAINER OR SIMILAR ARTICLE

Application filed June 15, 1932. Serial No. 44,084. Term of patent 7 years.

To all whom it may concern:

Be it known that I, HERMAN B. LERMER, a citizen of the United States, residing in the city of Newark, in the county of Essex and State of New Jersey, have invented a new, original, and ornamental Design for a Medicinal Container or Similar Article, of which the following is a specification, reference being had to the accompanying drawing, forming a part hereof.

In the drawing,

The figure represents a perspective view of a container embodying my new design.

I claim:

The ornamental design for a medicinal container or similar article, as shown.

HERMAN B. LERMER.
